UNITED STATES PATENT OFFICE.

JAMES W. LAFFERTY, OF KANSAS CITY, KANSAS.

CAR-BRAKE.

SPECIFICATION forming part of Letters Patent No. 764,667, dated July 12, 1904.

Application filed February 13, 1904. Serial No. 193,403. (No model.)

To all whom it may concern:

Be it known that I, JAMES W. LAFFERTY, a citizen of the United States, residing at Kansas City, in the county of Wyandotte and State of Kansas, have invented new and useful Improvements in Car-Brakes, of which the following is a specification.

My invention relates to improvements in car-brakes.

10 It relates particularly to car-brakes in which a shoe is applied to the wheel and rail.

The object of my invention is to provide a simple, effective, and durable brake provided with means by which the wheel-shoe may be applied by the wheel against the rail, thus greatly increasing the braking action, means being provided by which the shoe may be applied to the wheel and perform the braking action in the ordinary manner without making contact with the rail, said means providing, further, for the application by the wheel of the shoe to the rail in emergency cases.

20 The novel features of my invention are hereinafter more fully described, and set forth in 25 the claims.

In the accompanying drawings, which illustrate my invention, Figure 1 is a side elevation view of a portion of a car, showing connected therewith a braking mechanism constructed according to the principles of my invention. Fig. 2 is a view, partly in plan, partly in horizontal section, of part of the braking mechanism and portions of the car. Fig. 3 is a view, partly in vertical section and 35 partly in elevation, showing one end of the rock-shaft and some of the parts connected therewith. Fig. 4 is a vertical sectional view taken on the dotted line *a b* of Fig. 3. Fig. 5 is a rear elevation view of one of the wheel-shoes. Fig. 6 is a perspective view of the rail-shoe. Fig. 7 is a vertical sectional view taken on the dotted lines *c d* of Fig. 2, showing part of the means for rocking the rock-shaft. Fig. 8 is a cross-section taken on the 40 dotted line *e f* of Fig. 2.

45 Similar characters of reference indicate similar parts.

1 denotes the platform of a car; 2 and 3, two pairs of car-wheels, respectively.

50 4 denotes a transverse beam, to each end of

which is secured rigidly a wheel-shoe 5. The beams 4 are disposed, respectively, upon opposite sides of the wheels 2 and 3. Each of the shoes 5 is provided with a curved surface for engaging the periphery of the adjacent wheel. The under side of each shoe 5 is provided with a transverse dovetail recess in which is fitted a horizontal detachable rail-shoe 6, provided on its upper and lower sides with transverse corrugations 7, adapted to 60 make contact with the top of the rail 8. The shoe 6 is reversible, so that when the lower corrugated side becomes too much worn the shoe may be reversed in the recess of the wheel-shoe, with the upper corrugated side 65 placed below. A set-screw 9 is provided in each wheel-shoe 5 for securing therein the rail-shoe 6, upon which the set-screw bears.

Any convenient means may be employed for simultaneously moving the beams 4, so as 70 to apply all of the wheel-shoes 5 to the car-wheels. In the drawings I have shown the beams connected, respectively, by means of rods 10 and 11 with a horizontal lever 12, pivotally supported between the rods 10 and 11 75 in any suitable manner. A longitudinally-movable rod 13, movable by any suitable means, is connected at one end to the lever 12 for swinging the same to and fro to apply or release the brake-shoes 5. Transversely disposed beneath the car-platform 4 above each set of shoes 5 is a rock-shaft 14, the ends of which are supported, respectively, in transverse holes through brackets 15, supported upon the under side of the platform 1. Upon 80 each rock-shaft 14 are mounted two cams 16, disposed, respectively, adjacent opposite ends of the shaft. Upon each cam 16 is mounted a horizontal plate 17, which is raised and lowered when the rock-shaft is properly rocked. 90 To the upper end of each shoe 5 is secured the lower ends of two upwardly-extending rods 18, which extend through vertical holes provided, respectively, in the adjacent plates 17 at each side of the adjacent cam 16. En- 95 circling each rod 18 and supported at its lower end upon the plate 17 is a coil-spring 19, upon the upper end of which is supported a horizontal plate 20, provided with two holes through which the rods 18 extend. The up- 100

per ends of the rods 18 are screw-threaded and have mounted thereon, respectively, the nuts 21. The wheel-shoes 5 are provided, by means of the coil-springs 19, with a resilient support which normally retains the rail-shoes 6 out of contact with the rail 8. If the beams 4 are moved, as already described, so as to force the shoes 5 against the wheels 2 and 3, respectively, the brake-shoes 5 will be moved 5 in a direction corresponding to the direction of rotation of the wheels to which they are applied. If the car is moving in the direction indicated by the arrow in Fig. 1, the wheels 2 will force the shoes 5 downward against the pressure of the springs 19 and cause the rail-shoes 6 to be forced tightly against the rails 8, providing the rock-shaft 14 is in the position shown in Fig. 1. If it is desired to apply the wheel-shoes 5 to the wheels without 10 applying the rail-shoes 6 to the rails, the shaft 14 is rocked into the position indicated in Fig. 4, in which the cam 16 is turned by means of the rock-shaft 14, so as to raise the plate 17 to a height sufficient that the shoes 6 cannot 15 touch the rail when the shoes 5 are applied to the car-wheel even though the wheel is rotated in a direction such that the shoe 5 will be forced toward the rail. To so rock the rock-shaft 14, I provide the following mechanism: On the shaft 14 and rotatable therewith is mounted a pulley 22, over which runs a cable 23, secured at one point 24 to the periphery of the pulley 22. One end of the cable 23 is secured to one end of a coil-spring 25, the other end of which is secured to a 20 downwardly-extending bracket 26, rigidly secured to the under side of the platform 1. The other end of the cable 23 is secured to a rotatable shaft 27, extending vertically through 25 the platform 1 and provided at its upper end with a crank-arm 28, by which the shaft 27 is rotated. On the shaft 27, above the platform 1 and rotatable therewith, is mounted a ratchet-wheel 29, in the teeth of which engages a pawl 30, pivotally mounted upon the platform 1. To rock the rock-shafts 14 as viewed in 30 Fig. 1 to the position shown in Fig. 4, the shaft 27 is rotated, so as to wind thereon the cable 23, thus rotating the pulley 22 and rock- 35 ing the rock-shafts 14 as desired, the pawl 30 meanwhile engaging with the ratchet-wheel 29 and preventing the rearward rotation of the shaft 27. The cable 23, as shown in Figs. 8 and 2, is wound once around the left pulley 22', as viewed in Fig. 1, and secured thereto in any suitable manner. As the cable is drawn onto the shaft 27 it will rotate pulley 22' and the shaft 14, on which the said pulley is mounted, thus elevating the shoes 5 bearing 40 upon the wheels 3, as described with reference to the other brake-shoes 5. To retract the shafts 14 in the other directions, the pawl 30 is released from the ratchet-wheel 29, and the spring 25 through the intermediacy of the cable 23 and the pulleys 22 and 22' will rock 45

the shafts 14 to the positions shown in Fig. 1.

My invention may be modified in many ways without departing from its spirit.

Having thus described my invention, what I claim, and desire to secure by Letters Patent, is—

1. In a car-brake the combination with a wheel-shoe movable by the car-wheel toward the rail and provided with a transverse dovetail recess, of a rail-shoe fitted to said recess 75 and adapted to make contact with the rail when the wheel-shoe is properly moved, and means for locking said wheel-shoe in said recess.

2. In a car-brake the combination with the wheel-shoe movable by the car-wheel toward the rail and provided with means when properly positioned, to engage both rail and wheel, of means independent of the movement of the car-wheel for raising and lowering said wheel-shoe. 80

3. In a car-brake the combination with the wheel-shoe movable by the car-wheel toward and provided with means for engaging the rail, a yielding support for said wheel-shoe, 90 and means for raising and lowering said support.

4. In a car-brake the combination with the wheel-shoe movable by the wheel toward and provided with means for engaging the rail, of 95 means for normally retaining the shoe out of contact with the rail excepting when the shoe is applied to the wheel, and means for positioning the wheel-shoe for avoiding contact with the rail when the shoe is applied to the 100 wheel.

5. In a car-brake the combination with the wheel-shoe movable by the wheel toward and provided with means for engaging the rail, of resilient means normally retaining said 105 shoe out of contact with the rail excepting when the shoe is applied to the wheel, and means for so positioning said resilient retaining means as to prevent contact of the wheel-shoe with the rail when the shoe is applied to the 110 wheel.

6. In a car-brake the combination with the wheel-shoe movable by the wheel against the rail, a vertically-movable support, resilient means for mounting said shoe on said support 115 and normally holding the shoe free from the rail, and means for adjusting said support as to prevent contact of the shoe with the rail when the shoe is applied to the wheel.

7. In a car-brake the combination with a 120 wheel-shoe movable by the wheel toward and provided with means for engaging the rail, of a rock-shaft provided with a cam, and means for supporting the shoe upon said cam.

8. In a car-brake the combination with a 125 wheel-shoe movable by the wheel toward and provided with means for engaging the rail, of a rock-shaft, means for rocking the same, and means for raising the shoe when the shaft is properly rocked. 130

9. In a car-brake the combination with a wheel-shoe movable by the wheel toward and provided with means for engaging the rail, of a rock-shaft, means for rocking the same, a support, means for raising and lowering the said support when the shaft is rocked, and resilient means for supporting the wheel-shoe upon said support.

10. In a car-brake the combination with a wheel-shoe movable by the wheel toward and provided with means for engaging the rail, of a rock-shaft, means for rocking the same, a cam mounted on said shaft, a plate supported by said cam, one or more springs mounted on said plate, and means for supporting the wheel-shoe upon said spring or springs.

11. In a car-brake the combination with the wheel-shoe movable by the wheel toward and provided with means for engaging the rail, of a rock-shaft, means for rocking the said shaft in one direction, means for retracting the shaft in the opposite direction, and a vertically-adjustable resilient supporting means for the wheel-shoe, and means for vertically adjusting said resilient supporting means when the shaft is rocked in the proper direction.

12. In a car-brake, the combination with two wheel-shoes adapted each to engage a wheel and movable thereby toward and provided with means for engaging the rail, of a beam connecting said wheel-shoes, means for applying said shoes to the wheels, resilient means normally retaining said shoes clear of the rails excepting when the shoes are applied to the wheels with the wheels rotating in the proper direction, and means for positioning said resilient means so as to prevent contact of the wheel-shoes with the rail when the shoes are applied to the wheels.

13. In a car-brake, the combination with two pairs of wheel-shoes, the pairs being disposed respectively upon opposite sides of the wheels, means for applying simultaneously both pairs of shoes against their respective wheels, resilient supporting means sustaining each pair of shoes and permitting each pair, when applied to its respective pair of wheels and said wheels are moving in the proper direction, to be moved by said wheels toward and have contact with the rail, and means for adjusting said resilient means so as to prevent contact of the shoes with the rails.

14. In a car-brake, a wheel-shoe, means for pivotally mounting the same, means for swinging the shoe on its pivotal support against the wheel, means by which the shoe engages the rail when applied to the wheel and the wheel is properly rotated and means for positioning the shoe so contact will not be made with the rail when the shoe is applied to the wheel.

15. In a car-brake, the combination with the wheel-shoe movable by the wheel toward and provided with means for engaging the rail, of a rock-shaft, means for raising and lowering the wheel-shoe when the shaft is rocked in the proper directions, a spring for retracting the shaft in one direction, means for rocking the shaft in the opposite direction, and locking means for preventing retraction of the shaft by said spring.

16. In a car-brake, the combination with a rock-shaft provided with a cam, a wheel-shoe movable by the wheel toward and provided with means for engaging the rail, resilient means for supporting the shoe upon said cam, a rotatable shaft, a cable connected therewith, means for rocking the rock-shaft in one direction when the cable is wound on the rotatable shaft, and means for retracting the rock-shaft when the cable is released.

17. In a car-brake the combination with a rock-shaft, of a brake-shoe movable by the wheel toward and provided with means for engaging the rail, a plate, means for vertically adjusting said plate when the rock-shaft is rocked, one or more springs carried by said plate, means for supporting the brake-shoe upon said spring or springs, and means for applying the brake-shoe to the wheel.

18. A brake-shoe provided on one side with a surface for engaging the wheel and having a transverse recess, a rail-shoe having two opposite sides transversely corrugated mounted in said recess with one corrugated side in position for contact with the rail, the corrugated sides being reversible, and means for locking the rail-shoe in the recess.

In testimony whereof I have signed my name to this specification in the presence of two subscribing witnesses.

JAMES W. LAFFERTY.
